UNITED STATES PATENT OFFICE.

DUDLEY S. SEYMOUR, OF CHICAGO, ILLINOIS, ASSIGNOR TO UNION SPECIAL MACHINE COMPANY, OF CHICAGO, ILLINOIS, A CORPORATION OF ILLINOIS.

THREAD-CONTROLLER FOR SEWING-MACHINES.

1,147,048.

Specification of Letters Patent. Patented July 20, 1915.

Application filed September 26, 1912. Serial No. 722,465.

To all whom it may concern:

Be it known that I, DUDLEY S. SEYMOUR, a citizen of the United States, residing at 300 West Kinzie street, Chicago, in the county of Cook, State of Illinois, have invented certain new and useful Improvements in Thread-Controllers for Sewing-Machines, of which the following is a description, reference being had to the accompanying drawing and to the figures of reference marked thereon.

The invention relates to new and useful improvements in multiple needle sewing machines, and more especially to the tension 15 controlling means therefor.

An object of the invention is to provide means for simultaneously releasing the tensions of the several threads in a multiple needle machine, which means is controlled 20 by a knee shift or treadle which preferably operates to first raise the presser foot from the material, so that by the manipulation of the one device the presser foot may be raised and the tension released on all the needle 25 threads, whereby the material may be readily withdrawn from the machine.

In the drawings, which show by way of illustration, one embodiment of the invention, Figure 1 is a rear view of a sewing machine embodying my improvement. Fig. 2 is a plan view of the same. Fig. 3 is a perspective view of the tension supporting bracket, the tensions carried thereby, and the means for releasing the tensions. Fig. 35 4 is a perspective view of the releasing lever for the tension releasing mechanism. Fig. 5 is a vertical sectional view through the supporting bracket for the tensions and through a portion of the arms of the machine. Fig. 6 is a plan view on an enlarged 40 scale of a portion of the tension supporting bracket. Fig. 7 is a vertical sectional view through a portion of the tension supporting bracket, showing the releasing plate moved 45 to release the tension.

I have shown my improved tension releasing device as applied to a sewing machine having the usual work support 1, overhanging arm 2, in which reciprocates a needle bar 3, carrying a needle head 4, and a plurality of spaced needles 5, which are four in number, as herein illustrated. The needle bar is reciprocated by the needle lever 6, which is

operated by a strap and link connection 7 from the main shaft 8. 55

The material is held on the work support 1 by a presser foot 9, which is carried by a presser bar 10. The presser bar 10 is held depressed by a leaf spring 11, which bears on a pin 12, carried by a collar fixed to the 60 presser bar. The presser bar may be raised to lift the presser foot from the material by a lever 13, which is pivoted at 14 to the overhanging arm and projects forwardly so that its free end, when raised, will engage the pin 65 12, and lift the presser bar. The lever 14 is normally held depressed at its forward end by a spring 15. The rearwardly projecting part 16 of the lever 13 is connected to a chain or other flexible member 17, and this 70 flexible member is, in turn, connected with a treadle or knee shift, which is of the usual character.

Each of the needles is supplied with an independent thread. These needle threads are 75 led from the supply through tension devices 18, 19, 20 and 21, respectively. Each tension device consists of two flat disks 22 and 23, which are mounted on a stem 24, and held pressed together against a supporting 80 ledge 25 on the stem by a coil spring 26. The tension on the spring may be adjusted by a thumb nut 27. After leaving the tensions the threads are passed around suitable guiding pins 28, thence through automatic 85 clamping disks 29 to a guide for the threads 30, on the overhanging arm, and thence through a guide 31 on the needle lever to a guide 32 at the upper end of the needle bar, and thence down the needle head to the 90 needles. These tensions 18 to 21 inclusive are mounted on a bracket 33, which is formed with a shank 34, whereby said bracket is secured to the overhanging arm 2 of the machine by suitable screws 35. The bracket is 95 so constructed as to provide an extended shelf 36, which is arranged substantially horizontal. The stems 24 carrying the tension devices are rigidly secured to this shelf 36 and project upwardly therefrom. The 100 tension devices are preferably spaced so as to give a free passage for the threads therethrough. A rail 37 is rigidly attached to the shelf 36, and is provided with a plurality of spaced thread eyes 38, through which the 105 threads pass to the tension devices.

As a means for releasing the tension devices, I have provided a sliding plate 39, which is mounted to slide on the shelf 36, and on a projecting ledge 40, carried by the bracket 33. This plate is slotted, as at 41, and a guiding screw 42 passes through the slot into the ledge 40. The screw is provided with a flat head which overlaps the slot, and thus holds the plate on the ledge, but at the same time allows said plate to be moved freely back and forth. The plate is further guided by a second slot 43, and a screw 44 of similar character, which passes through the slot 43 into the shelf 36. These guiding screws permit the plate to slide back and forth on the shelf and ledge. The plate is cut away, as at 45, for each stem of the tension devices, so that the stems will not interfere with the free sliding of the plate. In Fig. 2, it will be noted that I have provided the plate with slots 46, whereby an additional tension may be placed on the supporting bracket, if desired.

The plate 39 carries two posts 47, each of which is provided with a cross bar 48. These posts 47 are so disposed relative to the tension devices that the cross bar lies in a plane passing between the tension disks 22 and 23. When the plate is at its extreme left hand position, as shown in Figs. 5 and 6, the cross bar is out of engagement with the tension disks 22 and 23, and the normal tension is exerted on the thread. When the plate 39, however, is moved to its extreme right hand position, as shown in Fig. 7, the cross bars 48 will be forced between the tension disks 22 and 23, which will separate said disks and thus release the threads from all tension.

As a means for moving the plate 39 back and forth, I have provided a rock lever 49. This rock lever is mounted on a projecting bracket 50, secured to the shank of the bracket 33 by suitable screws. The rock lever 49 has an upwardly projecting arm 51, which extends into an opening 52 in the plate 39. A coil spring 53 engages at one end the arm 51 and at its other end is connected to a lug 54, depending from the bracket 33. This spring normally holds the plate 39 with the cross bar 48 out of contact with the tension disks. The rock lever 49 is provided with a second arm 55, which is bent laterally, as at 56, so as to extend underneath the path of travel of the rearwardly projecting part 13 of the lever 13. The projecting end 56 is so positioned relative to the lever 13 that the first movement of the lever 13 will raise the presser foot from the material to a slight extent, after which said lever engages the projection 56, and swings the rock lever 49, so as to release the tensions. While I have so positioned the parts that the presser foot will be slightly raised before the tension is released, I have,

nevertheless, a construction whereby the presser foot is raised and the tensions simultaneously released, so as to free the threads from all tension, whereby the material may be readily withdrawn from the machine.

It will be obvious that minor changes in the details of construction and the arrangement of parts may be made without departing from the spirit of the invention, as set forth in the appended claims.

Having thus described the invention, what I desire to claim by Letters Patent is:

1. A combination of a plurality of needles, an independent tension for each needle thread, a supporting bracket on which said tensions are mounted, a plate slidably supported by said bracket and having means for simultaneously engaging or releasing the tensions, a presser foot, means for raising the presser foot and for sliding said plate to release said tensions.

2. The combination of a plurality of needles, an overhanging arm in which the needles reciprocate, a supporting bracket attached to said overhanging arm, and having a substantially horizontal shelf, a plurality of tensions mounted on said shelf, one for each needle thread, a plate slidably mounted on said shelf, and having means for simultaneously engaging and releasing the tensions, a rock lever for sliding the plate, and spring for normally holding said plate out of engagement with the tensions.

3. The combination of a plurality of needles, an overhanging arm in which the needles reciprocate, a supporting bracket attached to said overhanging arm, and having a substantially horizontal shelf, a plurality of tensions mounted on said shelf, one for each needle thread, a plate slidably mounted on said shelf, and having means for simultaneously engaging and releasing the tensions, a rock lever for sliding the plate, and spring for normally holding said plate out of engagement with the tensions, a presser foot, and means for raising said presser foot and for simultaneously oscillating said rock lever to release the tension.

4. The combination of a supporting bracket, a tension device carried by said bracket, a sliding plate having means to engage and release said tension device, a lever for operating said sliding plate, said bracket having an opening therethrough through which said lever extends to engage said sliding plate.

5. A sewing machine including in combination, a supporting bracket, a post carried thereby and extending perpendicular thereto, a tension mounted on said post, a sliding plate carried by said bracket and having enlarged openings through which said post extends, means carried by said sliding plate for releasing the tension, and means for sliding said plate on said bracket.

6. A sewing machine including in combination, a supporting bracket, a post extending perpendicular thereto, a tension device mounted on said post, a slide carried
5 by said bracket, a post mounted on said slide, a cross bar carried by the post for engaging and separating the tension devices.

In testimony whereof, I affix my signature, in the presence of two witnesses.

DUDLEY S. SEYMOUR.
